ERNEST W. SAUERMAN, OF CHICAGO, ILLINOIS, ASSIGNOR TO TRANSO PAPER COMPANY,
OF CHICAGO, ILLINOIS, A CORPORATION OF ILLINOIS.

CENTERING MEANS FOR ENVELOP-BLANK-CUTTING DIES.

1,132,979.

Specification of Letters Patent. Patented Mar. 23, 1915.

Application filed January 16, 1914. Serial No. 812,561.

To all whom it may concern:

Be it known that I, ERNEST W. SAUERMAN, a citizen of the United States, residing at Chicago, in the county of Cook and State of Illinois, have invented certain new and useful Improvements in Centering Means for Envelop-Blank-Cutting Dies, of which the following is a specification.

The present invention relates to a means for centering and properly positioning a cutting die for envelop blanks with respect to a transparent window formed in the blank, and is used in the manufacture of that style of envelopes known as window envelopes.

The objects of the present invention are to provide means whereby the blank will always be cut in a manner so that when folded into a complete envelop the window will lie in proper position on the face of the envelop.

A further object of the invention is to provide a mounting for this centering means so that it can move in accordance with the movement of the die and position itself so as not to interfere with the forcing of the die through the mass of paper in the blank forming operation.

The invention further consists in the features of construction and combinations of parts hereinafter described and claimed.

In the drawings: Figure 1 is a view showing a sheet of paper with a series of transparent windows formed thereon and the die of the present invention in operative position with respect to one of said windows; Fig. 2 is a section on line 2—2 of Fig. 1 looking in the direction of the arrow and showing the die in position prior to the cutting operation; and Fig. 3 is a view similar to Fig. 2 showing the die at the completion of the cutting operation.

As heretofore stated, the present invention is directed particularly toward a die which is used for cutting blanks for the so-called window envelopes, which is that class of envelopes having a portion of the front face made transparent so that when an inclosure is placed within the envelop the address upon the inclosure will show through the window and thus dispense with the writing of the address upon the face of the envelop. In manufacturing envelopes of this character it is highly important that the blank be cut in a manner so that when fold-

ed the window will assume the proper position upon the face of the envelop, for if such position is not assumed, the inclosure when folded and placed within the envelop will not have the address thereon in proper position to be exposed through the window. It is, therefore, of material importance to properly center the cutting die with respect to these windows.

Referring to the drawings, and particularly to Fig. 1 in this view, a sheet 4 of material is illustrated having formed thereon a series of transparent surfaces 5 which are of a shape and size to constitute the windows of the envelopes. The most expeditious way of manufacturing these envelopes is to form a plurality of transparent surfaces on a large sheet of paper, then place several sheets so formed in a pile, place the die on top of the pile and by one cutting operation cut out a plurality of envelop blanks. The transparent surfaces are placed on these sheets in such a manner as to allow the die to be placed in proper position with respect to these surfaces and yet eliminate, to all practical extent, any waste of material during the cutting operation, the transparent surfaces being spaced apart and positioned in a manner to allow the die to be positioned with respect to the same so that practically all of the stock is utilized for blanks.

The die itself comprises a body 6 which consists of a wall 7, a wall 8 and a wall 9 and as shown in the drawing is of a generally triangular nature. The walls, of course, being configured so as to create a blank that is of a form adapted to be folded into the complete envelop. The die is of a nature so that it constitutes a sort of a frame work and the centering member which forms the subject matter of the present invention lies within this frame work and hence is positioned inside of the confines of the die. This centering member as shown consists of a horizontally extending flat plate 10 from which extends a flat finger 11 at right angles thereto forming in effect a square of a nature similar to a carpenter's square. The plate 11 is formed with, or secured to the plate 10 by any suitable means and the plate 10 has attached thereto at its opposite ends stems 12 which slide within guides 13 and 14 affixed to plates 15 attached to the inner wall of the die member and springs 16.

surround these stems and bear upon the plate 11 at one end and against the guides 14 at the other end. Suitable means are provided to prevent the spring 16 from forcing 5 the stem down to a distance to have it pass out from engagement with the guides, the means shown consisting of a cross pin 17 and a removable locking member 18 is provided for the plate 15 so as to permit of its 10 adjustment up and down within the die, if such be desired.

It will be noted that the walls, 8 and 9 of the die are formed with inwardly extending 15 portions 19 which are necessary for proper formation of the envelop blank and advantage is taken of there inwardly extending portions or offsets to use them as a further guiding means for the centering member, the centering member being cut away 20 at its ends to form fingers 21 that ride along the walls of the offset portions 19.

In use the edge 22 of the plate 10 is placed along the longitudinal edge 23 of the window and the edge 24 of the plate 11 is placed along the end of the window, so that 25 the die is centered oppositely with respect to the window and hence the blank, when cut, will have all portions thereof in proper correlation to the window whereby when 30 the blank is folded the window will assume the proper position with respect to the face of the envelop. As the die is forced downward through the mass of sheets 4, which is accomplished by any suitable pressure 35 means, not shown, the plates 10 and 11 will remain upon the upper sheet of the pile of sheets. When the die is retracted or pulled out from the work the springs 16 will act to again send the centering means downward 40 in the die to the lower edge thereof and in proper position to be placed about another window and center the die with respect to this window.

The device is simple, does not require any 45 change whatsoever in the form of die now used, does not complicate or in any way affect the normal working of the die, and enables the blanks to be cut accurately with all speed that could be expected.

50 I claim:

1. A die for cutting blanks for window envelopes comprising a die portion, centering means within the confines of the die portion for centering the die with respect to the 55 window of the blank and a mounting for

said centering means permitting it to shift in accordance with the movements of the die through the work, substantially as described.

2. A die for cutting blanks for window envelopes comprising a die portion, centering means within the confines of the die portion for centering the die with respect to the window, a mounting for said centering means permitting said means to shift in accordance with the movement of the die 65 through the work and tension means for normally maintaining the centering means at the bottom of the die, substantially as described.

3. A die for cutting blanks for window 70 envelopes comprising a die portion, a centering means within the confines of the die portion, for centering the die with respect to the window, a mounting for said centering means permitting it to shift in accordance 75 with the movements of the die through the work and means for adjustably holding said mounting, substantially as described.

4. A die for cutting blanks for window envelopes comprising a die portion, a centering means within the confines of the die portion for centering the die with respect to the window, a mounting for the centering 80 means permitting it to slide up and down within the die, substantially as described. 85

5. A die for cutting blanks for window envelopes comprising a die portion, a centering means within the confines of the die portion for centering the die with respect to the window, a mounting for the centering 90 means permitting it to slide up and down within the die, and tension means for normally maintaining the centering means at the bottom of the die, substantially as described. 95

6. A die for cutting blanks for window envelopes comprising a die portion, a centering means within the confines of the die portion for centering the die with respect to the window, a mounting for the centering 100 means permitting it to slide up and down within the die, tension means for normally maintaining the centering means at the bottom of the die and means for adjustably holding said mounting in various positions, substantially as described. 105
